US0D1107897S

(12) **United States Design Patent** (10) Patent No.: **US D1,107,897 S**
 Lanigan et al. (45) Date of Patent: ** Dec. 30, 2025

(54) INFUSION SET COMPONENT AND ADHERING ASSEMBLY COMBINATION	D465,845 S 11/2002 Swenson
(71) Applicant: DEKA Products Limited Partnership , Manchester, NH (US)	D465,846 S 11/2002 Hwang
(72) Inventors: Richard J. Lanigan , Concord, NH (US); Connor E. Stadnicki , Epsom, NH (US); Jeffrey C. Marrion , Littleton, MA (US)	D476,418 S 6/2003 Spriek et al.
(73) Assignee: DEKA Products Limited Partnership , Manchester, NH (US)	6,589,229 B1 * 7/2003 Connelly A61M 5/14248 604/890.1
(**) Term: 15 Years	D484,242 S 12/2003 Wilkinson
(21) Appl. No.: 29/805,354	D484,976 S 1/2004 Wilkinson
(22) Filed: Aug. 26, 2021	D488,230 S * 4/2004 Ignotz D24/189
(51) LOC (15) Cl. 24-01	6,887,417 B1 5/2005 Gawreluk et al.

CLAIM

The ornamental design for an infusion set component and adhering assembly combination as shown and described.

DESCRIPTION

FIG. 1 is a top, front, right side perspective view of the infusion set component and adhering assembly combination showing the new design;

FIG. 2 is a front, top, right side, exploded perspective view thereof;

FIG. 3 is a front side elevational view of an infusion set component of the infusion set component and adhering assembly combination of FIG. 1;

FIG. 4 is a rear side elevational view of the infusion set component of FIG. 1;

FIG. 5 is a front, top, and right side perspective view of the infusion set component of FIG. 1;

FIG. 6 is a left side elevational view of the infusion set component of FIG. 1;

FIG. 7 is a right side elevational view of the infusion set component of FIG. 1;

FIG. 8 is a top plan view of the infusion set component of FIG. 1;

FIG. 9 is a bottom plan view of the infusion set component of FIG. 1;

FIG. 10 is a cross-sectional rear, top, left side perspective view of the infusion set component of FIG. 1 taken at the indicated cut plane in shown in FIG. 8;

FIG. 11 is a front elevational view of an adhesive liner backing of the infusion set component and adhering assembly combination of FIG. 1;

FIG. 12 is a rear elevational view of the adhesive liner backing of FIG. 1;

FIG. 13 is a front, top, right side perspective view of the adhesive liner backing of FIG. 1;

FIG. 14 is a right side elevational view of the adhesive liner backing of FIG. 1;

FIG. 15 is a left side elevational view of the adhesive liner backing of FIG. 1;

FIG. 16 is a bottom plan view of the adhesive liner backing of FIG. 1;

FIG. 17 is a top plan view of the adhesive liner backing of FIG. 1;

FIG. 18 is a cross-sectional view of the adhesive liner backing of FIG. 1 taken at the indicated cut plane shown in FIG. 16;

FIG. 19 is a cross-sectional view of the adhesive liner backing of FIG. 1 taken at the indicated cut plane shown in FIG. 16;

FIG. 20 is a front side elevational view of an adhesive patch of the infusion set component and adhering assembly combination of FIG. 1;

FIG. 21 is a rear side elevational view of the adhesive patch of FIG. 1;

FIG. 22 is a front, top, right side perspective view of the adhesive patch of FIG. 1;

FIG. 23 is left side elevational view of the adhesive patch of FIG. 1;

FIG. 24 is a right side elevational view of the adhesive patch of FIG. 1;

FIG. 25 is a bottom plan view of the adhesive patch of FIG. 1;

FIG. 26 is a top plan view of the adhesive patch of FIG. 1;

FIG. 27 is a left side elevational view of an adhering body of the infusion set component and adhering assembly combination of FIG. 1;

FIG. 28 is a right side elevational view of the adhering body of FIG. 1;

FIG. 29 is a front side elevational view of the adhering body of FIG. 1;

FIG. 30 is a rear side elevational view of the adhering body of FIG. 1;

FIG. 31 is a front, top, right side perspective view of the adhering body of FIG. 1;

FIG. 32 is a top plan view of the adhering body of FIG. 1;

FIG. 33 is a bottom plan view of the adhering body of FIG. 1;

FIG. 34 is right side elevational view of a second adhesive liner backing of the infusion set component and adhering assembly combination of FIG. 1;

FIG. 35 is a left side elevational view of the second adhesive liner backing of FIG. 1;

FIG. 36 is a front, top, right side perspective view of the second adhesive liner backing of FIG. 1;

FIG. 37 is a front side elevational view of the second adhesive liner backing of FIG. 1;

FIG. 38 is a rear side elevational view of the second adhesive liner backing of FIG. 1;

FIG. 39 is a top plan view of the second adhesive liner backing of FIG. 1;

FIG. 40 is a bottom plan view of the second adhesive liner backing of FIG. 1;

FIG. 41 is a right side elevational view of second adhering body of the infusion set component and adhering assembly combination of FIG. 1;

FIG. 42 is a left side elevational view of the second adhering body of FIG. 1;

FIG. 43 is a front, top, right side perspective view of the second adhering body of FIG. 1;

FIG. 44 is a front side elevational view of the second adhering body of FIG. 1;

FIG. 45 is a rear side elevational view of the second adhering body of FIG. 1;

FIG. 46 is a top plan view of the second adhering body of FIG. 1; and,

FIG. 47 is a bottom plan view of the second adhering body of FIG. 1.

The dash-dash broken lines in the drawings depict portions of the infusion set component and adhering assembly combination that form no part of the claimed design. The

dot-dash broken lines in the drawings depict the boundaries of the claim and form no part of the claimed design.
